UNITED STATES PATENT OFFICE

2,441,709

STRAIN INSULATOR

George H. Manke, South Milwaukee, Wis., assignor to Line Material Company, Milwaukee, Wis., a corporation of Delaware

Application June 21, 1945, Serial No. 600,824

3 Claims. (Cl. 174—176)

1

This invention relates to improvements in a strain insulator for guy wires or the like.

It is common practice to provide strain insulators for guy wires, comprising a wooden bar having metal fittings on the end adapted for engagement with the ends of guy wires. Failure of these insulators to withstand strains imposed thereon is frequent and may be attributed to deterioration of the wood or its inherent weakness at the points of connection with the fittings. Many attempts have heretofore been made to provide fittings which strengthen the wood at the points of engagement with the fittings and to provide fittings which will not by reason of the connection cause a weakening of the wood. These attempts have not been as successful as desired and, at most, are of a temporary nature due to weathering of the wood.

Another weakness inherent in wooden insulating strain bars is in the fact that some of the fibers become overloaded while others have not assumed their share of the strain, thus ultimately causing the overloaded fibers to fail and thereafter placing an overload on remaining fibers. This condition progresses from one set of fibers to another to a point where the bar ultimately fails by reason of a splitting action rather than because of the tension forces which it theoretically should withstand.

An object of this invention is to provide a weather resistant insulator bar that has a tensile strength much greater than wood and including fittings which effectively counter disruptive forces produced in the bar when subjected to excessive stresses.

Another object is to provide an insulator bar comprising impregnated - laminated material compressed to such density that further compression will not be effected when subjected to stresses tending to withdraw it from its fittings and which will be substantially free from shrinkage.

A further object is to provide an insulator bar comprising impregnated - laminated material which will prevent splitting of the bar intermediate the ends thereof and which will at all points transversely thereof assume a substantially uniform distribution of tension forces over corresponding cross-sectional areas.

In the drawings:

Fig. 1 is a fragmentary side view of a strain insulator embodying my invention.

Fig. 2 is a fragmentary top plan view of one of the end fittings and insulator shown in Fig. 1.

Fig. 3 is a sectional view taken on the line 3—3 of Fig. 2.

Fig. 4 is a side view of a modified fitting and fragmentary portion of an insulator bar embodying my invention.

2

Fig. 5 is a top plan view of the device shown in Fig. 4.

Fig. 6 is a view showing a modified form of fitting.

- 5 The strain rod which I propose to use comprises wood or fibrous laminations impregnated with a phenolic resin and compressed to a very dense condition, usually about one-half of the original thickness of the wood or fiber. The resulting insulator is substantially impervious to moisture, not subject to serious deterioration, and is not further compressible under the influence of stresses to which it may normally be subjected in use, as will more fully appear hereinafter.
- 10 Preferably, the strain insulator rod 1 is rectangular in cross-section so that the maximum available strength of the laminations may be utilized. As shown in Figs. 1, 2, and 3, the guy fittings at each end of the insulator rod comprise a pair of substantially identical members 2. Each member comprises an angle portion 3, one side of which extends beyond the other to provide a strain arm 4. Corresponding sides of the angle portions of the members are arranged on opposite sides of the rod and the arms 4 extend therefrom in parallel.

- 15 A bolt 5 extends through the longer sides of the members 2 and the rod 1, and nut 6 holds the longer sides in clamped engagement with the rod. A second bolt 7 extends through the shorter sides of the members 2 and the rod 1 and is more adjacent to the end of the rod than bolt 5. A nut 8 holds the shorter sides in clamped engagement with the rod.

- 20 The outer ends of the arms 4 support a bolt 9 upon which a grooved roller 10 is mounted. Nut 11 retains bolt 9 in position. The guy cable (not shown) is attached to the strain insulator by looping the end around the

- 25 roller 10 and clamping it to the body of the cable.

- 30 In operation, the strain insulator shown in Figs. 1, 2, and 3 operates as follows: Stresses tending to withdraw the rod 1 from the fittings tend to pull the bolts through the material of the 35 rod and to split it in planes paralleling the axes of the bolts. However, splitting of the rod is effectively prevented by reason of the clamping engagement of the member 2 with the rod, the 40 substantially non-compressibility of the material 45 of the rod, and the inherent strength of the 50 material.

- If desired, at least one side of the members 2 may be provided with an arcuate ridge 12 disposed about the bolt receiving hole 13 in the manner indicated in Fig. 6. This ridge serves to penetrate the adjacent surface of the rod 1 when the member 2 is clamped thereto, thus increasing the holding effect of the members upon the rod.

- In Figs. 4 and 5 the rod 1 is provided adjacent 55 its ends with opposed surfaces 14 and 15 diverg-

ing toward the ends. As in the previously described arrangement, the fittings at each end of the rod comprise two identical members 16. Each member is channeled to provide opposed divergent walls 17 and 18 corresponding to the divergent surfaces 14 and 15, respectively, on the rod. The bottom wall 19 of each member extends beyond the channel to provide an arm 20. Bolts 21 extend through adjacent side walls of the members 16 and nuts 22, threaded thereon, hold the members in clamped engagement with the rod 1. A bolt 23 extending through the arms 20 and nut 24 also holds the members 16 in clamped engagement with the rod.

A roller, such as 10 in Fig. 2, may be mounted between the arms 20 by means of a bolt extending through the coaxial holes 25 in the arms.

In operation, the strain insulator shown in Figs. 4 and 5 operates as follows: When the rod 1 is subjected to stresses tending to pull the ends from the fittings, the divergent surfaces 14 and 15 engage the opposed divergent walls 17 and 18 on the members and prevent withdrawal. The rod, being composed of impregnated, highly compressed material and substantially non-compressible in the arrangement shown, in co-operation with the fittings forms a joint that effectively withstands disruptive forces.

From the foregoing it will be apparent that the strain insulator herein disclosed is reliable in service because of its inherent strength and durability, is simple in construction, is easily and quickly assembled, is comparatively inexpensive, and is manipulated without difficulty when put into use.

I claim:

1. A strain insulator comprising an insulating member of resin impregnated and compressed laminations of wood, a pair of fittings attached to said insulator at opposite ends thereof, each of said fittings comprising a pair of angle plates and a plurality of nuts and bolts, each of said bolts extending through each of said angle plates and said insulator member in right-angle relation to each other, said angle plates conjointly forming an expansion limiting means resisting expansion of said ends in two relative right angle directions.

2. The combination with a rod-like insulator of impregnated and compressed laminations of wood having an end rectangular in cross-section and a pair of relatively spaced transverse holes in said end each disposed in spaced relationship to the other longitudinally of said rod

and with its axis disposed at right angles to the other and normal to opposed sides of said end, of a fitting embracing said end and comprising two identical interchangeable members, each member including an angle portion provided with an aperture each in registry with one of said holes and an arm extending from said end, bolts extending through said holes and apertures, and nuts on said bolts clamping corresponding sides of said members to corresponding opposed sides of said ends.

3. In a strain insulator, the combination with an elongated substantially impervious non-compressible insulating rod having an end of rectangular cross-section, said end having a pair of transverse apertures each spaced longitudinally of said rod relative to the other and having its axis normal to the axis of the other, said apertures each with its axis normal to opposite sides of said end, of a fitting embracing all sides of said end and including a pair of substantially identical members, each member having side portions in right angle relationship and contiguous to corresponding sides of said end, one of said side portions extending beyond the other and beyond said end to form a strain arm, the strain arm of each member being in parallel relation to the other and spaced therefrom, each of said side portions having an aperture in alignment with the transverse aperture in the side of said end contiguous thereto, bolts extending through said apertures, and clamping nuts on said bolts holding corresponding sides of said members in clamped relationship to said end, said members embracing all sides of said end and jointly opposing expansion of said end in each of two relative right angle directions.

GEORGE H. MANKE.
